UNITED STATES PATENT OFFICE.

ISAAC HAMMER, OF NEW YORK, N. Y.

DOOR-LOCK.

1,289,742.

Specification of Letters Patent. Patented Dec. 31, 1918.

Application filed July 17, 1918. Serial No. 245,391.

To all whom it may concern:

Be it known that I, ISAAC HAMMER, a citizen of the United States, and a resident of the city of New York, borough of the Bronx, in the county of Bronx and State of New York, have invented a new and Improved Door-Lock, of which the following is a full, clear, and exact description.

Among the principal objects which the present invention has in view are: to provide a lock adjustable for being released by a key; to provide means for throwing a bolt operable at both sides of a door; to provide an adjustment at one side of the lock so arranged that the lock may not be operated from the opposite side thereof; and to simplify the construction of the lock.

Drawings.

Figure 1 is a face view showing a fragment of a door having a knob for operating the herein disclosed lock and a key plate for assisting therein;

Fig. 2 shows a fragment of the reverse side of the door and of the lock and shackles therefor;

Fig. 3 is a detail showing a fragment of the lock, the adjusting lever being thrown into one of the many positions to which it may be moved;

Fig. 4 is a similar view showing the adjusting lever moved in the opposite direction;

Fig. 5 is a vertical section of the lock, the section being taken as on the line 5—5 in Fig. 6;

Fig. 6 is a horizontal section of the construction shown in Fig. 5, the section being taken as on the line 6—6 in Fig. 5;

Fig. 7 is a detail view showing part of the operating mechanism of the lock as mounted on the bottom plates thereof;

Fig. 8 is a detail view showing the bolt-throwing mechanism with which the lock is provided.

Description.

As seen in the drawings, the lock is provided with a case 12. The case 12 has an extension 13 in which squared perforations 14 are formed for the passage of shackles 15. The shackles 15 are perforated to receive the bolts 16 when said bolts are moved therethrough. The side walls of the perforations 14 are provided with perforations to

align with the perforations in the shackles 15 when said shackles are fully extended through the perforations in the extension 13. The bolts 16 are integrally mounted on a body portion 17. The body portion 17 has a slot 18 formed therein, through which extends a guide bar 19. The body portion 17 has a recess 20 to receive the ward arms 21 and 22, respectively, for moving the body portion to project and retract the bolts 16. The ward arms 21 and 22 are mounted on the short shafts 23 and 24, respectively. The shaft 23 has fixedly attached thereto a mutilated ratchet wheel 25, the teeth of which are normally engaged by a pawl 26, to prevent the retractive rotation of said ratchet wheel. The pawl 26 is normally held in engagement with the ratchet wheel 25, by a spring 27, when said pawl is rocked on the pivot 28 by the operation of the lever 29. Normally the body portion 17 and bolts 16 connected therewith are held in extended position by the lug 30. The lug 30 is normally engaged by an offset 31 on the latch lever 32. The latch lever 32, as shown best in Fig. 8, is pivotally mounted on the body portion 17 by the stud shaft 33. The latch lever 32 has a lateral extension 34, which extends into the recess 20 in the path of the arms 21 and 22. The office of the extension 34 is to enable the arms 21 and 22 to lift the lever 32, and the free end thereof having the offset 31 with the result that the shoulder of the offset 31 is lifted out of engagement with the lug 30. This arrangement of the lever 32 admits of the retraction of the body portion 17 and the bolts 16 connected therewith.

As seen best in Fig. 8 of the drawings, the offset 31 of the latch 32 falls behind and engages from the rear side, the lug 30. In this position, the body portion 17 and bolts 16 are prevented from being advanced or moved to engage the shackles 15.

The recess 20 above referred to is formed between the lateral extensions 35, the lower surfaces of which are curved to form cut-away portions 36, which permit the passage of the arms 21 and 22. The latch 32 is normally held against the lug 30 by a spring 37. The shafts 23 and 24 are provided with manipulating handles 38 and 39, respectively. The handle 39 is at the outside of the door adjacent the key plate 40. The

shaft 24 with which the handle 39 is connected, is provided with the ratchet wheel 25, as seen best in Fig. 7 of the drawings.

To release the said wheel, the pin barrel 41 of a cylinder lock is rotated to the position shown by solid lines in Fig. 7 of the drawings, where the extension 42 is shown as lifted under the tail of the lever 29. The short end of said lever rocks said pawl to 10 lift the tooth thereof out of engagement with said wheel. The pin barrel 41 is rotated by means of a key 43, which enters the keyway 48 at the outside of the door 49. The crank 46 is pivotally attached to the 15 pin 45. The shank 50 of the button 47 rides on the edge of the plate 51.

When the button 47 is in the position indicated by broken lines in Fig. 5 of the drawings, the lever 29 may be operated by 20 rotating the key barrel 41 and extension 42 to lift the pawl 26 from engagement with the wheel 25. When the button 47 is moved to the position indicated by broken lines in Fig. 4 of the drawings, the shank 50 of the 25 said button passes below the edge of the plate 51, to prevent the lift of the lever 29, thereby rendering it impossible to turn the pin barrel 41, or to dislodge the pawl 26 from engagement with the wheel 25. When 30 the button 47 is carried to the upper edge of the button 51, as indicated in Fig. 3 of the drawings, the lever 29 is held permanently in position so that the pawl 26 is permanently disengaged from the wheel 25. 35 The effect of the movement of the button 27 to the three positions is as follows: A person on leaving the room closes the door 49, the shackles 15 passing through the perforations 14 in the extension 13, so that 40 the perforations in the shackles and side walls of the extension 13 align with the bolts 16. The handle 39 is then turned to shoot the bolts 16, the arm 22 entering the recess 20 between the extensions 35 to first lift 45 the lever 32 and to advance the body portion 17 and bolts 16. At the full forward movement of the body portion 17, the arm 22 passes out of the recess 20, permitting the extension 34 and the lever 32 connected 50 therewith to drop so that the offset 31 passes behind the lug 30.

The person returning to the door cannot move the handle 39 and shaft 23 connected therewith retractive, for the reason that 55 the pawl 26 has engaged the teeth of the wheel 25 to prevent the reverse rotation of the shaft 24. To release the pawl, the party must use the key 43. With the key 43 inserted in the pin barrel 41, the same may be 60 turned until the extension 42 is lifted to the position shown in Fig. 5 of the drawings, which rocks the lever 29 to lift the toothed end of the pawl 26. This frees the ratchet wheel 25 and permits the rotation of the 65 shaft 24, with the effect that the arm 21

connected therewith enters the recess 20 to lift the lever 32 and offset 31 out of engagement with the lug 30. The continuation of the rotation of the shaft 24 results in retracting the body portion 17 and bolts 16 70 out of engagement with the shackles 15. The door is then free to be opened.

To withdraw the key 43, it is necessary to re-rotate the pin barrel 41, which permits the reengagement of the pawl 26 with the 75 wheel 25. Therefore, it is obvious that the handle 39 cannot be turned to effect the withdrawal of the bolts 16. The bolts 16 are shot by turning the handle 39 after the 80 person has closed the door, from the inside of the room, the shaft 23 and arm 22 being operated to this end.

If it is desired to leave the lock so that the door may be opened from the outside by turning the handle 39, at any time, the 85 button 47 is moved to the position shown in Fig. 8. In this position, the lever 29 is rocked and held in the position where the pawl 26 is disengaged from the ratchet wheel 25. While the parts are in this position, both shafts 24 and 23 are freely rotatable.

If it is desired to prevent the door from being opened from the outside by the use of the key 43, the button 47 is moved to the 95 position shown in Fig. 7 of the drawings. In this position, the lever 29 is held from rocking and maintained out of engagement with the pawl 26 which continues to engage the wheel 25 to prevent the retractive 100 rotation of the shaft 24 and handle 39.

When installing the lock, the shackle block 52 is held by screws to the door frame, said screws being preferably driven from the side of the block, the heads of the screws 105 resting between said block and the edge of the door, thereby rendering it substantially impossible to remove or force the block 52.

Claims.

110

1. A door lock comprising a body portion having an engagement recess formed therein and provided with a bolt connected therewith; a plurality of shafts for engagement with said body portion for moving the 115 same; means for preventing the retractive rotation of one of said shafts, said means embodying a ratchet toothed member rigidly mounted upon the shaft to be controlled, and a pawl member for engaging said 120 ratchet toothed member; and means for rendering inoperative said means for preventing the retractive rotation, said means embodying a key-controlled mechanism operable for disengaging said pawl member from 125 said ratchet toothed member.

2. A door lock comprising a reciprocatory body member, said member carrying locking bolts and having an engagement recess for moving said body member to and from 130

- the active service position of said lock; a plurality of shafts, each having a handle extended from said lock in opposite directions and each provided with an extension 5 adapted for engaging said recess for moving said body portion; a stop member rigidly mounted in said lock in fixed relation; a latch pivotally connected with said body member for engaging said stop member to prevent the movement of said body 10 member; and means operatively connecting said latch and said shafts for lifting said latch out of engagement with said stop member.
- 15 3. A door lock comprising a reciprocating body member, said member carrying locking bolts and having an engagement recess for moving said body member to and from the active service position of said lock; a plurality of shafts, each having a handle extended from said lock in opposite directions and each provided with an extension 20 adapted for engaging said recess for moving said body portion; a stop member rigidly mounted in said lock in fixed relation; a latch pivotally connected with said body member for engaging said stop member to prevent the movement of said body member; and means operatively connecting 25 said latch and said shafts for lifting said latch out of engagement with said stop member rigidly mounted in said lock in fixed relation; a latch pivotally connected with said body member for engaging said stop member to prevent the movement of said body member; and means operatively connecting 30 said latch and said shafts for lifting said latch out of engagement with said stop member, said means embodying an extension of said latch normally resting in the path of the extensions on said shafts in 35 said recess of said body member to be lifted thereinto to elevate the engaging end of said latch.
4. A door lock comprising a reciprocating body member, said member carrying locking bolts and having an engagement recess for moving said body member to and from the active service position of said lock; a plurality of shafts, each having a handle extended from said lock in opposite directions and each provided with an extension 45 adapted for engaging said recess for moving said body portion; a stop member rigidly mounted in said lock in fixed relation; a latch pivotally connected with said body member for engaging said stop member to prevent the movement of said body member; and means operatively connecting 50 said latch and said shafts for lifting said latch out of engagement with said stop member; means for controlling one of said shafts for preventing the retractive rotation thereof, said means embodying a ratchet wheel rigidly mounted on said control shaft, and a pawl normally engaging said ratchet wheel; and a key-controlled rotary member having an extension for rocking said pawl out of engagement with said ratchet wheel; and a key-controlled rotary member having an extension for rocking said pawl out of engagement with said ratchet wheel.
- 55 5. A door lock comprising a reciprocating body member, said member carrying locking bolts and having an engagement recess for moving said body member to and from the active service position of said lock; a 60
- bolts and having an engagement recess for moving said body member to and from the active service position of said lock; a plurality of shafts, each having a handle extended from said lock in opposite directions 70 and each provided with an extension adapted for engaging said recess for moving said body portion; a stop member rigidly mounted in said lock in fixed relation; a latch pivotally connected with said body member for engaging said stop member to prevent the movement of said body member; means operatively connecting said latch and said shafts for lifting said latch out of engagement with said stop member; means for controlling one of said shafts for preventing the retractive rotation thereof, said means embodying a ratchet wheel rigidly mounted on said control shaft, and a pawl normally engaging said ratchet wheel; and a key-controlled rotary member having an extension for rocking said pawl out of engagement with said ratchet wheel; and means for controlling the movement of said latch, said means embodying a rocking lever engaging said latch, and an adjustable device controlling the position of said lever, said device being manually operable at the inner side of said lock.
- 65 6. A door lock comprising a reciprocating body member, said member carrying locking bolts and having an engagement recess for moving said body member to and from the active service position of said lock; a 75
- 95
- 100
- 105
- 110
- 115
- 120
- 125
- 130

plurality of shafts, each having a handle extended from said lock in opposite directions and each provided with an extension adapted for engaging said recess for moving said body portion; a stop member rigidly mounted in said lock in fixed relation; a latch pivotally connected with said body member for engaging said stop member to prevent the movement of said body member; means operatively connecting said latch and said shafts for lifting said latch out of engagement with said stop member; means for controlling one of said shafts for preventing the retractive rotation thereof, said means embodying a ratchet wheel rigidly mounted on said controlled shaft, and a pawl nor-

mally engaging said ratchet wheel; a key-controlled rotary member having an extension for rocking said pawl out of engagement with said ratchet wheel; means for controlling the movement of said latch, said means embodying a rocking lever engaging said latch, and an adjustable device controlling the position of said lever, said device being manually operable at the inner 25 side of said lock; and a guide plate for holding said device in position where said lever holds said latch inoperatively or prevents said key-controlled member from operating said latch at the will of the operator.

ISAAC HAMMER.
